LOOM FROG.

Application filed October 2, 1926. Serial No. 139,088.

This invention relates to protector mechanisms for looms and is more particularly directed to the construction of the sliding frog used in such looms to effect loom stoppage when the shuttle fails to properly box or becomes trapped in the shed.

It is now the usual practice to provide looms with a protector mechanism to effect loom stoppage when the shuttle fails to be properly boxed and such mechanism usually includes a frog at one or both sides of the loom frame which is slidably mounted and normally held in its rearward position by resilient means against the tension of which the protector mechanism or dagger on the lay acts when the shuttle fails to box or gets caught in the shed, to thereby effect loom stoppage before the full beat-up movement of the lay. In such mechanisms as heretofore constructed, the frog acts upon a train of mechanism to stop the loom when the frog is moved frontwardly, and such frogs are usually formed with a partially closed bottom portion having a frontwardly extending element to act upon a cushion which returns the frog to its rear position after a "bang-off".

One of the objects of the present invention is to provide a loom frog having an open bottom and supported for sliding movement by a frog support upon which the open bottomed frog may be readily assembled.

In accordance with the present invention, the frog is normally held in its rearward position by a cushion of elastic material, such as rubber or the like, which substantially fills the recessed frog between a fixed thrust wall and the back wall of the frog, and means are provided in connection therewith to confine the frog to sliding movements towards and from the front of the loom.

In accordance with another feature of the present invention, the frog is provided with a safety pin which will insure frog stoppage before the lay completes its frontward movement.

The invention and various features thereof will best be made clear from the following description and the accompanying drawings of one good form thereof.

In the drawings:

Fig. 1 is a sectional side elevation at one side of the loom, showing the protector mechanism and improved frog; and

Fig. 2 is a view of the loom frame and frog in disassembled relation.

The loom frame 1 may be of usual construction and have associated therewith the shipper handle 2 pivotally supported at 3 and normally held in loom running position. Pivotally mounted at 4 on the loom frame is a knock-off 5, the end portion 6 of which bears against the shipper and the lower end portion 7 of which is in the path of frontward movement of the frog, to be herein-after described. The construction described may be of usual character and may be modified in various ways without departing from the true scope of the present invention, the essentials in this respect being that when the frog is moved frontwardly by the protector mechanism or dagger on the lay, it will effect loom stoppage.

The lay 8 is provided with the usual shuttle box 9 and binder 10 against which rests the finger 11 carried by an arm 12 mounted on the rock shaft 13 carried by the lay. At each side of the loom (where a frog is to be used at each side) the shaft 13 is supplied with a dagger 14, the construction being such that should the shuttle fail to properly box or be trapped in the shed, one of the daggers 14 will engage the frog and move it frontwardly to effect loom stoppage.

The loom frame 1 has a frog support 15 which, in the present instance of the invention, is formed as a member 15 secured either to the loom frame or made as part thereof. Extending through the support 15 is a recess 16 which contains the frontwardly extending filler portion 17 of a thrust wall 18. The thrust wall 18 is of substantially the same size as the recess in the open bottomed frog.

Frontward of the recess 16 the frog support is provided with an opening 19 through which passes a safety pin to be herein-after described, and the purpose of which is to insure stoppage of the frog before the lay completes its frontward movement.

The frog 20 is provided with the side members 21 between which and the top of the frog is the frog recess (as indicated in Fig. 2) which embraces the frog support 15.

Between the rear wall 22 of the frog and the thrust wall 18 is inserted a block of elastic material 23 and such block of elastic material substantially fills the entire recess por-

tion of the frog between the thrust wall 18 and the rear wall 22, the construction being such that the large section of elastic material, such as rubber, may be utilized at 5 the time of bang-off to arrest forward movement of the frog under the action of the protector mechanism before the lay completes its forward movement. The interposition of a large section of elastic material 10 23 between the thrust wall 18 and the rear wall 22 of the frog enables the full body of the elastic material to be utilized to arrest forward movement of the frog, a condition which is essential in protector mechanisms 15 because if the frog were not arrested before the lay completes its front movement, the lay would continue forwardly, with the result that the shuttle, trapped in the shed, would break out the warp threads.

20 The frog 20 has its portion rearward of the rear wall 22 slotted, as at 24, thus forming at each side of the slot 24 guide members 25 connected to the body of the frog by the inclined walls 26, thereby imparting 25 strength and stability to the frog under the lifting action that is liable to occur when the loom bangs-off.

Secured to the loom frame rearward of the frog is the frog stop and guide 27 which 30 may be appropriately held in fixed position by means of a bolt 28. The forwardly extending portion 29 of the frog stop and guide overlies the guide members 25 projecting rearwardly from the frog, and the frog 35 guide and stop has at its front a stop portion 30, which, when the frog is moved rearwardly by the block of elastic material 23, rests against the back surface of the frog back wall 22. The frog stop and guide 40 is thus constructed to not only guide the frog in its forward and rearward movements, but effectively prevent any lifting action of the rear end portion of the frog when the loom bangs off.

45 Under ordinary working conditions, the block of elastic material 23, such as rubber or the like, will be sufficient to act through its entire cross-sectional dimensions to arrest forward movement of the frog before the 50 lay completes its forward movement, and will by its bodily elastic character return the frog to its rearward position when the lay is moved back or the dagger released from the frog.

55 It may happen at times that the block of elastic material or rubber 23 may fail to effectively perform its arresting function and, in accordance with the present invention, a safety pin is provided to insure stoppage of the frog before the lay completes its forward movement.

In the present instance of the invention the frog 20 is provided with the side members 31 which embrace the side portions of 65 the frog support 15 and extending between

the lugs 31 is a safety bolt 32 which passes through the elongated slot 19 in the frog support. The end portions of the safety pin 32 may be secured to the frog lugs 31 in any approved manner but, as shown in the present instance of the invention, the safety pin 32 is non-circular in cross-section and at each end thereof it is provided with a circular cross-sectional portion 33 which engages corresponding openings 34 in the frog lugs 75 31. The safety pin may appropriately be held in its operative position in the slot 19 and connected to the frog by means of the cotter pins 35, as indicated in Fig. 2, although any appropriate means may be provided for this purpose.

As hereinbefore stated, the safety pin 32 is of non-circular cross-section and such portion of the safety pin is contained within the elongated slot 19 of the frog support, 85 so that as the frog is moved forwardly, the safety pin partakes of such movement and at a predetermined point of its forward travel, the safety pin is met by a stop which effectively prevents further forward movement of the frog. In the present instance of the invention, the safety pin stop 90 consists of a cushioning material 36 mounted in the front portion of the elongated slot 19, and in order that such cushioning material may not yield sufficiently to permit the frog to move forwardly, it is made less yielding than the block of elastic material 23, with the result that should the block of elastic material 23 permit the frog 100 to move forwardly to bring the safety pin 32 against the stop 36, the latter will act to effectively stop any further forward movement of the frog. In the present instance of the invention, the safety pin stop 36 may be 105 formed of leather, which, while having some yield, is less elastic than the elastic material or rubber block 23. It is desirable that the safety pin stop 36 be made slightly yielding, because the full momentum of the 110 lay may be exerted against such material and its slight elasticity will prevent breakage of parts.

The safety pin 32 has its active portion of non-circular cross-section, as above noted, 115 and this is desirable because it will not indent or become embedded in the cushioned stop 36 upon repeated use. Moreover, the safety pin 32 may be assembled in the described relation with different faces of the 120 non-circular stop surfaces brought into cooperative relation with the stop 36.

The open bottom frog recessed as hereinbefore described and provided with the block of elastic or rubber material 23 may 125 be readily assembled upon existing looms, and the frog stop and guide which overlies the rear end portion of the frog will act to permit forward and rearward movement of the frog while restraining any lifting at 130

the rear end thereof. The safety pin 32, as will be readily apparent, is passed through the slot 19 of the frog support and its circular end portions are mounted in lugs 31 of the frog. In order to facilitate assembly, one of the openings 34 in the frog lugs 31 is made somewhat larger than the other, as shown, and on the safety pin 32 is a circular portion 37 corresponding in size with the large opening 31, with the result that the open bottom frog may be placed upon the frog support and the safety pin may then be passed endwise through the larger opening 34, the slot 19 with the smaller end 33 engaged with the smaller opening 34. This is a good practical construction, but obviously various detailed constructions may be employed within the true scope of the invention.

20 What is claimed is:

1. A protector mechanism for looms, comprising a frog support, a recessed frog having an open bottom and back wall and slidably mounted upon the frog support, a frog stop and guide secured to the loom frame and overlying portions of the frog, a fixed thrust wall within the recess of the frog, and a block of rubber material coextensive with the space between the thrust wall and back wall of the frog when the latter is in its rearward position that the full section of such material may be effective in cushioning the frontward movement of the frog, a safety pin carried by the frog, and an elastic stop of less elasticity than the block of rubber material to stop the frog before the lay completes its frontward movement.

2. A protector mechanism for looms, comprising a frog support, a recessed frog having an open bottom and back wall and slidably mounted on the frog support, a thrust wall mounted on the support within the recessed frog, a block of rubber substantially filling the space between the thrust wall and back wall of the frog that the full section

thereof may be effective in cushioning the frontward movement of the frog, a safety pin carried by the frog, and a stop in the path of the safety pin for arresting frontward movement of the frog prior to the full frontward movement of the lay.

3. A protector mechanism for looms, comprising a frog support, a recessed frog having an open bottom and rear wall and mounted on the support, a frog stop and guide acting upon the rear portion of the frog to confine it to movements towards and from the front of the loom, a fixed thrust wall within the recess of the frog, a block of elastic material substantially filling the recess of the frog back of the thrust wall for engagement by the rear wall of the frog that the full section of said material may be effective to arrest frontward movement of the frog, a safety pin having a stop surface of non-circular cross-section and secured to the frog, and a stop less yielding than the said elastic material for engagement by the non-circular portion of the safety pin to insure arrest of the frog prior to the full beat-up movement of the lay should the block of elastic material fail to do so.

4. A protector mechanism for looms, comprising a frog support, a recessed frog having an open bottom and a back, a frog stop and guide acting upon the rear portion of the frog to confine it to movements towards and from the front of the loom, a fixed thrust wall within the recess of the frog, a yielding cushion within the recess of the frog back of the thrust wall, a safety pin having a stop portion of non-circular cross-section and secured to the frog, and a stop less yielding than said yielding cushion for engagement by the non-circular portion of the stop pin to insure stoppage of frontward movement of the frog before the lay completes its beat-up.

In testimony whereof, I have signed my name to this specification.

HARRY A. DAVIS.
